FOOD AND BEVERAGE SERVER

Robert B. Karoff, New York, N. Y., assignor to Novelty Utilities, Inc., New York, N. Y., a corporation of New York

Application May 11, 1955, Serial No. 35,914

Term of patent 7 years

(Cl. D44—10)

FIG. 1.

FIG. 2.

FIG. 3.

Fig. 1 is a vertical elevational view of the food and beverage server, showing my new design;

Fig. 2 is a plan view thereof; and

Fig. 3 is a side elevational view thereof.

A basket is shown in the drawing for purposes of illustration only. The dominant features of my design reside in those portions shown in full lines.

I claim:

The ornamental design for a food and beverage server, as shown and described.
